ATTORNEY

UNITED STATES PATENT OFFICE.

SAM SCHINBURG, OF NEW YORK, N. Y.

TURRET.

SPECIFICATION forming part of Letters Patent No. 678,429, dated July 16, 1901.

Application filed October 25, 1900. Serial No. 34,391. (No model.)

To all whom it may concern:

Be it known that I, SAM SCHINBURG, a subject of the Czar of Russia, residing at the city of New York, county and State of New York, have invented certain new and useful Improvements in Turrets, of which the following is a specification.

This invention relates to new and useful improvements in turrets for heavy ordnance; and its primary object is to provide a device of simple and durable construction and so formed as to receive the least injury from projectiles coming in contact therewith.

A further object is to provide means of novel construction whereby the ordnance may be held at any desired inclination.

With the above and other objects in view the invention consists in the details of construction and in the arrangement and combination of parts to be hereinafter more fully set forth and claimed.

I have illustrated my invention by the drawings accompanying and forming part of this specification, in which—

25 Figure 1 is a top plan view of the turret with the gun in a horizontal position. Fig. 2 is a central vertical section; and Fig. 3 is a front view of the mouth, showing in detail the manner of securing the gun.

30 Referring to the drawings, A is the turret, formed of suitable metal and secured at its base to any desired structure. This turret has at the front end the shape of a cone B, terminating at an opening *h*, having preferably outwardly-inclined edges *b*. The opening is adapted to receive a gun G, about which is secured two similar frames C and D, recessed, as shown at *g*, to receive the trunnions *g'*, and these frames are clamped together in 40 any suitable manner. The frames are so ta-

pered at their edges as to fit over the edges of the opening *h*, as shown.

It will be seen that the gun may be brought to any desired inclination and that the recoil of said gun will be received by the wall of the 45 opening *h*.

From the above it is thought that those familiar with the art can easily and fully understand the operation of the invention.

It will readily be seen that by providing a 50 turret with a face having an inclined surface, as described, the projectiles contacting therewith will glance off without doing any material damage thereto.

In the foregoing description I have shown 55 the preferred form of my invention; but I do not limit myself thereto, as I am aware that modifications may be made therein without departing from the spirit or sacrificing the advantages thereof, and I therefore reserve 60 the right to make such changes as may fairly fall within the scope of my invention.

Having fully described my invention, what I claim as new, and desire to secure by Letters Patent, is—

65 The combination with a turret having a front face tapered toward its center and an opening in the center thereof, of a gun within the opening, a collar clamped thereto, and forming bearings for the trunnions of the 70 gun, and tapered edges to the collar adapted to engage the walls of the opening.

In testimony whereof I have signed my name to this specification, in the presence of two subscribing witnesses, this 24th day of 75 August, 1900.

SAM SCHINBURG.
